UNITED STATES PATENT OFFICE.

DAVID H. WILSON, OF CHICAGO, ILLINOIS, ASSIGNOR TO ROBERT BINES,
OF CHICAGO, ILLINOIS.

TELEPHONE SYSTEM.

No. 830,271.

Specification of Letters Patent.

Patented Sept. 4, 1906.

Application filed January 2, 1906. Serial No. 294,250.

To all whom it may concern:

Be it known that I, DAVID H. WILSON, a citizen of the United States, residing at Chicago, in the county of Cook and State of Illinois, have invented a certain new and useful Improvement in Telephone Systems, of which the following is a specification.

This invention relates to telephone systems, and has for its object to provide a new and improved system of this description.

This invention is illustrated in the accompanying drawings, wherein—

Figure 1 is a diagrammatic view showing one construction embodying the invention. Fig. 2 is a view showing the instrument at one end of the line as operated on a grounded circuit.

As is well known, one of the difficulties encountered in telephone systems is the disturbance due to induction on the line. One of the objects of the present invention is to obviate the evils due to this cause.

As shown herein, there are provided a set of instruments at each end of the line comprising a transmitter A, a receiver B, and an induction-coil C. The induction-coil has two cores D and E. The core D has a primary coil D' and a secondary coil D'', while the core E has a primary coil E' and a secondary coil E''. The primary coils D' E' are connected in multiple and are in circuit with the transmitter A and the source of current-supply A'.

The secondary coils D'' E'' are connected in series in the main line F, leading to the instruments at the distant station. Between the cores D and E is a core G, containing a single coil G', connected in circuit with the receiver B and without a battery or other source of current-supply.

It will be seen that the receiver is electrically independent of both the primary and secondary circuits and is in a circuit having no electrical connection with the transmitter-circuit or the main line over which the message to be received is transmitted. It will further be seen that the coil in the receiver-circuit is wound upon a core by itself and containing no other coil.

Core D has pole-pieces H, core G has pole-pieces I, and core E has pole-pieces J. The pole-pieces of the various cores are preferably magnetically insulated from each other, as shown by the insulating-pieces L.

It will be seen that in the construction of Fig. 1 the receiver-coil is on a core magnetically separated from the core of the primary and secondary coils.

In operating the device the operator talking into the transmitter causes a current to go out on the line in the ordinary manner. When the current reaches the receiving-station, it acts upon the cores D and E, so as to energize them, and they in turn energize the core G.

The variations in the current due to the action of the transmitter at the other end cause a variation in the magnetic circuit of the cores D and E, and this variation affects core G so as to induce a talking-current in coil G', which is transmitted into speech by the receiver B free from any and all external induction effects in the main line.

By means of this construction the rattling and other disagreeable noises produced in the receiver by induction on the line are obviated, and messages may be sent for longer distances than is possible when the inductive effects are present.

It will be seen that in this construction the receiver is in a circuit which is cut off conductively, both electrically and magnetically, from the main line over which the talking-current is transmitted.

I claim—

1. A telephone system comprising a primary and a secondary circuit wound upon a core, a receiver-circuit electrically independent of the primary and secondary circuits and wound about a core located in proximity to said first-mentioned core so as to be influenced thereby.

2. A telephone system comprising a transmitter-circuit and a line-circuit, a portion of each of said circuits being wound about a core, a receiver-circuit, a core therefor about which a portion of said circuit is wound, said latter core in proximity to the core about which a portion of the transmitter and line circuits are wound, but magnetically insulated therefrom.

3. A telephone system comprising a transmitter-circuit containing a transmitter and a source of current-supply, a line-circuit leading to the distant station, two iron cores about which a portion of each of said circuits is wound, an intermediate iron core, a re-

ceiver-circuit electrically independent of the other two circuits and having a portion wound about said intermediate core.

4. A telephone system comprising a transmitter-circuit containing a transmitter and a source of current-supply, a line-circuit leading to the distant station, two iron cores about which a portion of each of said circuits is wound, an intermediate iron core, a receiver-circuit electrically independent of the other two circuits and having a portion wound about said intermediate core, said several cores being magnetically insulated from each other.

15 5. A telephone system comprising a transmitter-circuit containing a transmitter and a

source of current-supply, a line-circuit leading to the distant station, two iron cores about which a portion of each of said circuits is wound, the windings of the transmitter-circuit on the two cores being connected in multiple and the windings of the main-line circuit being connected in series, an intermediate iron core, a receiver-circuit electrically independent of the other two circuits and having a portion wound about said intermediate core.

DAVID H. WILSON.
